UNITED STATES PATENT OFFICE

WILLIAM C. BALKE, OF CRANNELL, CALIFORNIA

LOOPING AEROPLANE SWING

Application filed March 14, 1930. Serial No. 435,865.

The present invention relates to a looping aeroplane swing and has for its prime object to provide a swing with mechanism operable by an occupant therein to put the swing in motion and to cause it to loop about the stationary shaft mounted in a stand.

Another very important object of the invention resides in the provision of a swing of this nature which will afford considerable amusement, thrills, exercise of a healthy nature and which is of simple construction, inexpensive to manufacture, strong and durable, adjustable, and thoroughly efficient and reliable in use and operation.

With the above and numerous other objects in view as will appear as the description proceeds, the invention resides in certain novel features of construction, and in the combination and arrangement of parts as will be hereinafter more fully described and claimed.

In the drawings:

Figure 1 is a front elevational view of the apparatus embodying the features of my invention,

Figure 2 is a fragmentary side elevational view with parts broken away to show the manner in which the operating means are applied to the swing body,

Figure 3 is a detail vertical longitudinal section through the swing showing the operating mechanism,

Figure 4 is a detail sectional view through the seat,

Figure 5 is a detail view of the rocker,

Figure 6 is a sectional view taken substantially on the line 6—6 of Figure 5,

Figure 7 is a top plan view of the sliding power rods,

Figure 8 is a detail sectional view taken substantially on the line 8—8 of Figure 9,

Figure 9 is a detail section taken substantially on the line 9—9 of Figure 3,

Figure 10 is a perspective view of one of the foot rests,

Figure 11 is a detail sectional view through the upper end of the stand,

Figures 12, 14 and 15 are sectional views taken substantially on the lines 12—12, 14—14 and 15—15 respectively of Figure 11,

Figure 13 is a detail sectional view taken substantially on the line 13—13 of Figure 3.

Referring to the drawings in detail, it will be seen that numeral 5 denotes a rectangular base frame from which rises a stand S which

supports at the top thereof a pair of aligned relatively spaced brackets B. Supported between the brackets B is a stationary shaft 19 that is secured in position through the medium of U-bolts 40 and held against rotation 60 by means of lugs 41 rising from the brackets and engaging recesses provided in the shaft 19.

Shaft 19 intermediate the ends thereof is provided with a crank 7. A connecting rod 4 is pivotally connected at its upper end to the crank 7 by a crank pin 18. The purpose of the connecting rod 4 will be hereinafter made manifest.

A pair of swing supports 6 provided at 70 their upper ends with saddles 5', the same being in the nature of plates secured to said ends of the support and provided with anti-friction bearings 67. The aforementioned saddles 5' are mounted on the shaft 19 as 75 shown between collars 68 that are adjustably engaged with said shaft, and fixed collars 69.

Each of the swing supports 6 have diverging portions connected at their lower ends to the fuselage of a swing structure simulating the structure of an aeroplane. A suitable propeller 43 is mounted on the front end of the fuselage.

Opposite frame bars of the fuselage are designated by the reference character 46, and adjacent the forward end of the fuselage, there is mounted on the frame bars brackets 48 in which is journalled a rock shaft 16. Mounted on the rock shaft 16 is a sleeve 49 that is keyed to the rock shaft through the medium of a suitable set screw 50'.

Sleeve 49 is provided with a rocker arm 50, and the connecting rod 4 at its lower end is bifurcated and straddles the free end of the arm 50. The bifurcated end of connecting rod 4 is pivotally engaged as at 63 with the arm 50 as suggested in Figure 3.

Sleeve 49 on opposite sides of the arm 50 is provided with a pair of arms 3, and the arms 3 of each pair of arms extend at substantially right angles to the rocker arm 50.

Each pair of arms 3 support between their free ends a guide rod 21 that is provided intermediate its ends with oppositely disposed trunnions 52 rockable in the extremities of the arms 3.

Each of the rod guides 21 has slidably therethrough a power rod 2. On each rod 2 adjacent the rear end of the guide 21 is slidably mounted a sleeve 22, and a coil spring 110

23 is disposed about the rod 2 and arranged between the sleeve 22 and a shoulder 54 provided by enlarging the rear end of the rod 2.

Rearwardly of the shaft 16 is mounted a fixed transverse shaft 25 that has its ends supported in brackets 45 supported on the frame members 46. On the shaft 25 is rockably mounted a pair of levers or sticks 1, there being one lever or stick for each rod 2. Sticks 1 are adapted to be rocked or rotated relative to shaft 25, and each stick at its lower end is provided with a series of relatively spaced openings 47 adapted to be selectively aligned with a selected one of a series of openings 57 provided on the rear of a rod 2, a bolt 58 engaging the aligned openings 47 and 57 whereby to pivotally connect the free end of the power rod 2 with its control stick 1.

Each rod 2 adjacent its rear end has adjustable thereon a saddle 8 that is retained at the desired adjustment on the rod 2 through the medium of a bolt 55 engageable with a selected one of a series of notches 56 provided on the rod 2.

Each saddle 8 has a stud 60 rising therefrom and a foot rest 15 is rockably engaged with the stud and retained in operative engagement with the stud through the medium of a suitable lock nut 26.

Each foot rest 15 is substantially T-shaped as suggested in Figure 10 and the cross head of the foot rest at its ends has flanges 61 and 62 depending therefrom, flange 62 being longer than the flange 61 and being capable of engaging the rod 2 for limiting swinging movement of the foot-rest bar in one direction.

Preferably, the swing or car F is large enough to accommodate two occupants. For the occupants, there is suitably provided in the swing, a seat 11, and the occupants of the swing when seated, may engage with their feet, the foot rests 15 and at the same time with their hands grip a stick 1 which will extend upwardly between the legs of each occupant.

In operation, preferably two persons occupy the swing as above suggested, and with their feet push on the foot rests 15 and with their hands gripping the sticks 1 pull the sticks toward them, with the result that there is exerted on each rod 2 a push and pull and obviously by continuously alternately pushing and pulling on the sticks 1, the swing will gather momentum as it swings back and forth. As the momentum increases, the swing will be caused to move in the arc of a circle about the fixed shaft 19. The above operation is thought apparent from the fact that an occupant or occupants by pushing with the feet on the foot-rest bar 15, and pulling the lever 1 toward him will, through the medium of the connection between the lever 1 and the shaft 16, cause the latter to rotate 65 in an anti-clockwise direction or toward the

left in Figure 3 causing the swing body or car to swing or move toward the left in Figure 3. The lever 1 is then swung in an opposite direction causing a reverse rotation of shaft 16 resulting in a swinging of the swing body or car toward the right there being of course at this time no push being exerted by the feet on the rudder bar 15.

As a safety means, there is provided for the occupants of the car F a suitable safety belt 12 that may be buckled or otherwise secured at its ends to the sides of the fuselage, with an intermediate portion of the belt passing through a guide loop 13 suitably anchored to the seat 11 for position between the occupants of the swing.

As is thought apparent, saddles 8 may be adjusted relative to the power shafts 2, and the connections between the power shafts 2 and the sticks 1 may be also easily effected to accommodate either a grown person or a small child. Furthermore, the adjustments for one person may be made without disturbing the adjustments previously made on the other side of the swing for the second occupant of the swing so that if desired both a grown person or adult and a child may occupy the swing at the same time without inconvenience to either.

Of course, the swing may be controlled by a single occupant, in which case, the controls are adjusted in the same position on both sides, and in which instance, the operator would then sit between the two sticks 1 and take one stick in each hand. The foot rests 15 are then swung to the dotted line positions shown in Figure 7 and the shank portions of the foot rests thus provide a rest for the feet of the single occupant.

The power rods 2 being slidable relative to the guide sleeves 21 will prevent the sticks 1 with which said rods are engaged, from being forced back to such an extent as might injure the occupant or occupants.

The rods 2 being slidable, also relieves compression strain on the connecting rod 4. Suitable means for maintaining the movable parts in a well lubricated condition are provided, the hood H of the swing being easily removable to gain access to such parts of the swing as may be located under the hood. There is also provided for each of the guides 21 a suitable lubricant device 24.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of

the invention as hereinafter claimed or sacrificing any of its advantages.

Having thus described my invention, what I claim as new is:

5 1. A swing comprising in combination a stand, a horizontal shaft fixedly supported on the upper end of said stand and having a crank portion, a pair of hanger members rotatably mounted on said shaft, a car supported between the lower ends of said hangers, a rock shaft journalled transversely of said car, a rocker arm on said rock shaft, a connecting rod pivotally connected at one end with the crank portion of said first mentioned shaft, and at its lower end being pivotally connected with said rocker arm, and manual control means for rocking said rock shaft.

2. In a swing of the character described, 20 a fixed horizontally mounted shaft having a crank portion, supporting means for said shaft, hanger members rotatably mounted on said shaft and normally depending therefrom, a carriage supported between said hanger members, a rock shaft journalled in said carriage, a connecting rod operatively connecting said rock shaft with the crank portion of the first mentioned shaft, a control stick mounted in said carriage, a power rod, 30 means operatively connecting said power rod with said rock shaft, and means operatively connecting said power rod with said stick whereby, upon rocking of said stick, movement is transmitted to said rock shaft for swinging said carriage relative to the first mentioned shaft.

3. A swing comprising in combination a stand, a car, means for suspending said car from said stand for swinging movement relative to said stand and means for swinging said car, said means including a fixed shaft mounted above said car and having a crank portion, a rock shaft mounted in said car, a rocker arm fixed on said rock shaft, a connecting rod pivotally connected at one end with said rocker arm and pivotally connecting at its opposite end with the crank portion of said fixed shaft, and manual means for rocking said rock shaft.

4. A swing comprising in combination a fixed shaft, hangers rotatably mounted on said shaft and normally depending therefrom, a car supported between said hangers, a rock shaft journalled in said car, and having a sleeve secured thereon and provided with a rocker arm, a connecting rod pivotally connected at one end with said first mentioned shaft laterally of the said shaft and at its opposite end with said rocker arm, a guide sleeve, means pivotally mounting said guide sleeve on said first mentioned sleeve, a power rod having an end portion slidable through said guide sleeve, a sleeve slidable on said power rod, yieldable means engaging said rod and said slidable sleeve and normally

urging said slidable sleeve into engagement with said guide sleeve, a pivotally mounted stick supported in said car, and means for adjustably connecting said stick with said power rod.

5. A swing comprising in combination a fixed shaft, hangers rotatably mounted on said shaft and normally depending therefrom, a car supported between said hangers, a rock shaft journalled in said car, and having a sleeve secured thereon and provided with a rocker arm, a connecting rod pivotally connected at one end with said first mentioned shaft laterally of said shaft and at its opposite end with said rocker arm, a guide sleeve, means pivotally connecting said guide sleeve to said first mentioned sleeve, a power rod having an end portion slidable through said guide sleeve, a sleeve slidable on said power rod, yieldable means engaging said rod and said slidable sleeve and normally urging said slidable sleeve into engagement with said guide sleeve, a pivotally mounted stick supported in said car, and means for adjustably connecting said stick with said power rod.

6. In a device of the character described, and in combination a rock shaft, supporting means therefor, a sleeve mounted on said rock shaft for rotation therewith, two pairs of arms projecting radially from said sleeve, a guide sleeve rotatably mounted between the arms of each pair of arms, a pair of power rods, there being one power rod for each of said guide sleeves, and each of said power rods having one end slidable through its guide sleeve, means on said power rods engageable with the guide sleeve of each of said power rods, a pair of sticks pivotally mounted on said supporting means, there being one stick for each power rod, means operatively connecting each stick to its power rod, whereby upon rocking movement of said sticks power will be transmitted to said rock shaft.

7. In a device of the character described, a rock shaft, supporting means therefor, a pair of parallel arms projecting radially from the rock shaft, a guide sleeve rotatably mounted between said arms, a pivotally mounted member, a power rod connected with said member and having one end extending through said guide sleeve, and means on said power rod engaging said guide sleeve.

In testimony whereof I affix my signature.

WILLIAM C. BALKE.
